UNITED STATES PATENT OFFICE.

EUGENE GREGORY, OF MICHIGAN CITY, INDIANA, ASSIGNOR, BY MESNE ASSIGNMENTS, TO NATIONAL FRESH AIR FURNITURE COMPANY, OF RENO, NEVADA, A CORPORATION OF NEVADA.

SPRING-BED-BOTTOM FABRIC.

1,011,052.

Specification of Letters Patent.

Patented Dec. 5, 1911.

Original application filed April 13, 1911, Serial No. 620,903. Divided and this application filed June 12, 1911. Serial No. 632,721.

To all whom it may concern:

Be it known that I, EUGENE GREGORY, of Michigan City, in the county of Laporte and State of Indiana, have invented certain new and useful Improvements in Spring-Bed-Bottom Fabrics; and I hereby declare that the following is a full, clear, and exact description thereof, reference being had to the accompanying drawings, which form 10 part of this specification.

This invention is a novel improvement in spring bed bottoms, and resides in the novel construction thereof hereinafter described.

The object of the invention is to provide a 15 novel form of spring mattress or bottom for beds; which will afford ample support for every portion of the bedding placed thereon, and will yield at the portions where the most pressure is exerted thereon, so as to comfortably adjust itself to the body of the 20 wearer; and will maintain its shape and flexibility under very hard and long usage with scarcely any appreciable wear; and which moreover can be attached to a bed or 25 frame without being put under such tension, as ordinary spring bed bottoms require.

The bed bottom in brief consists of a 30 metal fabric made up of single wire figure eight springs ending in short hooks, these 35 springs hooking laterally and longitudinally into rings of wire to form the complete body of the fabric; and this fabric bottom is attached to the frame or rails, by any convenient means, preferably by wire loops passing 40 through the rails.

I will now explain the invention in detail with reference to the accompanying drawings which show a spring bed bottom embodying the invention.

45 In said drawings—Figure 1 is a top plan view partly broken of a complete bed bottom, the upholstered mattress being partly broken away. Fig. 2 is an enlarged detail view of several of the spring members of the bed-bottom and their connections. Fig. 3 is an edge view of Fig. 2. Fig. 4 is an enlarged detail view of the bed bottom springs and its wire loops by which the springs are connected to the frame.

50 In Fig. 1 of the drawings I have shown my novel bed bottom or fabric as applied to a folding bed. This is fully described in my application for folding bed or couch filed April 13, 1911, Serial No. 620,903, of which

the present application is a division; it is 55 therefore unnecessary herein to describe the folding frame in detail, and the invention is not restricted to any particular construction of frame, bed or couch to which the bed bottom is attached. 60

As shown in the drawings the bed bottom fabric is composed of members 4 (preferably wire rings) arranged in following order; to every ring is connected four peculiar wire springs 5; each spring 5 (except those 65 at the outermost sides of the fabric) is interposed between and connects two adjacent rings 4. Each spring 5 is preferably made of a single stiff steel wire which is bent intermediate its ends into an approximately 70 figure 8 shape, forming two flat loops 5^a lying in substantially the same plane, while the two ends of the wire 5^b are extended in opposite directions from between the loops but in substantially the same plane; and 75 the extremities of these ends or arms 5^b of the spring are hooked as at 5^c, to engage the rings. The spring members are so proportioned that the flat loops of the spring members and the rings, or devices equivalent to 80 the rings are so close together that a silver dollar could hardly find space to drop face-wise through the bed bottom at any point; and in such bottom practically every part of any superposed body, such as an upholstered mattress M placed on such a bed bottom, will be directly supported. 85

The outermost spring members 5 at the sides and ends of the wire bottom are connected to the adjacent side bars 1, 1^a and end 90 bar 1^b of a supporting frame which may be of any suitable construction. As shown wire loops 6 are attached to the side bars 1, 1^a, 1^b; and the outer arms of the outside spring-members 5 are directly engaged with 95 these wire loops 6; while the outer arms of the outermost end spring-members 5 may be connected to the loops on the ends of the frame by means of wire links 6^a, as I have found it is unnecessary in practice to extend 100 the spring fabric the entire length of the frame, it being sufficient if it extends under such portions of the mattress as will be subjected to the weight of a person lying thereupon. 105

In order to enable the bed bottom to be folded straight across the center of the spring-bottom if desired, I may substitute

for the central transverse row of spring-members 5, helical springs 7, which extend across the bed bottom. The outermost springs 7 may be connected with plates 7^a attached to the bars 1, 1^a of the same section of the top frame as described in my aforesaid application; these plates 7^a can be screwed or bolted to the said bars in any suitable manner. With this construction 10 when the frame is extended the spring mattress lies flat and smooth and taut, without any excessive contracting pressure upon the members of the frame, such as would tend to distort the latter or such as would be 15 necessary with a woven wire mattress. By reason of the peculiar form of the springs the bed-bottom is very thin and yet covers the surface almost as closely as a woven wire mattress. By reason of the 20 peculiar curvature of the springs the bed-bottom or fabric will readily depress in curves, not in angles, at the place where the most pressure is applied thereon,—as at the shoulders or hips of a person lying there- 25 upon,—without unduly distorting any other portion of the mattress; and it will not sag and become "hammocked" like ordinary springs.

What I claim is:

1. A spring fabric or bottom for beds, 30 comprising a series of spring-members each bent into opposite coils approximately resembling a figure 8, the ends of the wire extending in opposite directions from between the coils of such figure and lying in 35 substantially the same plane as the coils, and intermediate members engaged by the said spring-members.

2. A spring bottom for beds, comprising a 40 series of members or rings arranged in parallel rows, and a series of spring-members each formed of a stout wire bent into opposite flat coils lying in substantially the same plane and approximately resembling a figure 8, with the ends of the wire extended in 45 opposite directions from between the coils to form arms in substantially the same plane as the coils, said arms being engaged with the rings to form a fabric.

In testimony that I claim the foregoing as 50 my own, I affix my signature in presence of two witnesses.

EUGENE GREGORY.
